ABSTRACT

A real-time environmental model of a shared virtual environment (SVE) including a plurality of virtual persons and a plurality of virtual gaming devices is provided. Display data corresponding to the SVE is transmitted to a first player device worn by a first player, the display data including user display data that causes a display device in the first player device to render a portion of the SVE based on a virtual orientation of the first player device and a virtual location of the first player in the SVE. A player preference associated with the first player is determined. Based on the player preference, one of an appearance and a behavior of a first virtual person of the plurality of virtual persons in the SVE being displayed by the first player device is modified.

CUSTOMIZED DISPLAY OF VIRTUAL PERSONS IN A VIRTUAL REALITY ENVIRONMENT BASED ON USER PREFERENCES

BACKGROUND

Embodiments described herein relate to virtual reality environments, and in particular to customized display of virtual persons in a virtual reality gaming environments, such as virtual casino environments, based on user preferences, and related devices, systems, and methods. As the adoption of virtual reality (VR) technology becomes more widespread, many companies are developing persistent virtual worlds that include simulated and/or enhanced reproductions of real world locations, including gaming environments such as casinos for example. There is a need for 10 to populate these worlds with virtual persons to provide a more realistic and desirable experience for users. While the amount of digital “real estate” for these worlds is effectively unlimited, conventional virtual worlds may populate these worlds with artificial, e.g., system-controlled or artificial intelligence (AI)-controlled, virtual persons, to provide a more realistic experience for players interacting with these 15 virtual worlds.

BRIEF SUMMARY

According to some embodiments, a system includes a processor circuit and a memory including machine-readable instructions. When executed by the processor circuit, the instructions cause the processor circuit to provide a real-time environmental model of a shared virtual environment (SVE) comprising a plurality of virtual persons and a plurality of virtual gaming devices. The instructions further cause the processor circuit to transmit display data corresponding to the SVE to a first player device worn by a first player, the display data including user display data that causes a display device in the first player device to render a portion of the SVE based on a virtual orientation of the first player device and a virtual location of the first player in the SVE. The instructions further cause the processor circuit to determine a player preference associated with the first player. The instructions further cause the processor circuit to, based on the player preference, modify one of an appearance and a behavior of a first virtual person of the plurality of virtual persons in the SVE being displayed by the first player device.

According to some embodiments, a virtual-reality player device includes a head-wearable frame, a display device coupled to the frame to position the display device in a field of view of a player, a processor circuit, and a memory including machine-readable instructions. When executed by the processor circuit, the instructions cause the processor circuit to receive display data corresponding to a shared virtual environment (SVE) comprising a plurality of virtual persons and a plurality of virtual gaming devices. The instructions further cause the processor circuit to render, by the display device, a portion of the SVE based on a virtual orientation of the gaming device and a virtual location of the player in the SVE. The instructions further cause the processor circuit to determine a player preference associated with the player. The instructions further cause the processor circuit to, based on the player preference, modify one of an appearance and a behavior of a first virtual person of the plurality of virtual persons in the SVE being displayed by the display device.

According to some embodiments, a method includes providing, by a processor circuit, a real-time environmental model of a shared virtual environment (SVE) including a plurality of virtual persons and a plurality of virtual gaming devices. The method further includes transmitting display data corresponding to the SVE to a first player device worn by a first player, the display data including user display data that causes a display device in the first player device to render a portion of the SVE based on a virtual orientation of the first player device and a virtual location of the first player in the SVE. The method further includes determining, by the processor circuit, a player preference associated with the first player. The method further includes, based on the player preference, modifying, by the processor circuit, one of an appearance and a behavior of a first virtual person of the plurality of virtual persons in the SVE being displayed by the first player device.

BRIEF DESCRIPTION OF SEVERAL VIEWS OF THE DRAWINGS

FIG. 1 is a schematic block diagram illustrating a network configuration for a plurality of gaming devices according to some embodiments.

FIG. 2A is a perspective view of a gaming device that can be configured according to some embodiments.

FIG. 2B is a schematic block diagram illustrating an electronic configuration for a gaming device according to some embodiments.

FIG. 2C is a schematic block diagram that illustrates various functional modules of a gaming device according to some embodiments.

FIG. 2D is a perspective view of a gaming device that can be configured according to some embodiments.

FIG. 2E is a perspective view of a gaming device according to further embodiments.

FIGS. 2F and 2G illustrate VR/AR devices according to various embodiments.

FIG. 3A is a map of a gaming area, such as a casino floor, according to some embodiments

FIG. 3B is a 3D wireframe model of the gaming area of FIG. 3A, according to some embodiments.

FIGS. 4A and 4B are views of a shared virtual environment (SVE) 404 corresponding to fields of views (FOVs) of a plurality of players wearing head-mounted virtual reality devices, according to some embodiments.

FIGS. 5A-5C are overhead views of a SVE showing movement of virtual persons around the SVE, according to some embodiments.

FIG. 6 is a flowchart illustrating operations of systems/methods of facilitating participation in a wagering game between multiple devices, according to some embodiments.

DETAILED DESCRIPTION

Embodiments described herein relate to virtual reality environments, and in particular to customized display of virtual persons in a virtual reality gaming environments, such as virtual casino environments, based on user preferences, and related devices, systems, and methods.

Embodiments described herein may be used in connection with virtual environments, e.g., VR environments, as well as real environments with virtual elements, e.g., augmented reality (AR) or mixed reality (MR) environments. For example, one example of a VR implementation may facilitate a player at home using a VR headset to experience the virtual casino or other environment. An example of an AR

implementation may have a player in an actual casino environment and using an AR device to augment the experience.

In addition, while many embodiments are described in terms of gaming devices, such as Electronic Gaming Machines (EGMs), aspects of the disclosure may also be used with other types of gaming devices, such as sports wagering terminals, kiosks, table games, etc., and other elements that may be found in a casino floor environment, such as restaurants, retail shopping, or other services, for example.

In a conventional VR implementation, one or more virtual players may be associated with a particular shared virtual environment (SVE), such as a virtual casino environment for example. In this implementation, a virtual person associated with each player would interact with the virtual environment and be visible to other players in the same SVE. Embodiments disclosed herein also contemplate virtual persons associated with a single player existing in multiple SVEs simultaneously, thereby providing the illusion of various virtual casino environments being filled with more real-world players or being busier than they otherwise would be. For example, a player may be playing an EGM in a particular virtual casino, and may also be displayed in a different virtual casino playing the same type of EGM. One advantage of this arrangement is that a greater proportion of virtual persons in these virtual casinos can be associated with real-world players, which may result in greater realism and immersion for other players in the virtual casinos.

In some examples, the behavior of the player in the primary casino environment, i.e., the casino environment with which the player is directly interacting, may be duplicated across additional virtual casinos. The system may also modify behaviors for different environments and/or players interacting with the virtual player in other environments, to better correspond with the environment. For example, a player may be unable to displace another player from a virtual EGM in the other player's primary environment, but may be able to cause the system to displace the other player in the other player's non-primary environment, to free up that particular virtual EGM for the player that is actually interacting with that environment, e.g., by approaching or attempting to play the EGM.

Embodiments described herein may be used with virtual reality (VR), augmented reality (AR), mixed reality (MR), or other systems in a gaming environment, such as a casino environment. Embodiments may also be used in connection with real or virtual devices, such as Electronic Gaming Machines (EGMs), sports wagering terminals, kiosks, table games, and/or other devices in a casino floor, shopping, restaurant, retail, or other environment. For example, an example using VR may include a player using a VR headset in any environment, such as a home environment, to experience a virtual casino. An AR example may include a player visiting a real world casino and using an AR device to augment the experience.

In some embodiments, a virtual casino may include virtual players. Virtual players can be used to simulate a busy or crowded environment, and the environment can be customized to provide different impressions for players. For example, the virtual EGMs in the environment can be made to seem hot or lucky by having the virtual players win often. The virtual players might be customized to attract certain players to certain areas for marketing reasons. For example, the virtual players in a particular area might all be wearing football jerseys to attract players who are interesting in football. The virtual players could be customized to attract

players of a certain demographic such as a younger or older age group, e.g., to target a certain demographic or player style to a casino environment, an area within the casino, and/or a particular machine within the casino. For example, the virtual players and/or environment may be customized to attract sports fans to new virtual sports betting machines that are being introduced. In an AR example, the new sports betting terminal might be a physical terminal, with virtual elements and/or virtual players drawing players to the terminal.

In some embodiments, the virtual players may be controlled by patterns or scripts. The casino operator or host system can assign certain scripted virtual players to perform actions on the casino floor. For example, one script might have a virtual player wander around the casino while another script might have a virtual player sit at an EGM and play a specified amount, e.g., for a specific amount of time, or for a specific amount of coin-in, with periodic wins and bonus games.

In some embodiments, the behavior of the virtual players may be controlled using artificial intelligence (AI) or machine learning (ML). For example, virtual players may follow AI/ML models such as "high roller", "tourist", "family", etc. and act autonomously according to their model. Alternatively, or in addition, the models may be built using an expert system (a collection of fixed rules, etc.) to approximate the behavior of different types of players.

In some embodiments, the virtual players may be based on recordings of previous behavior by real players or simulated players, e.g., replays of player actions from another time, casino, etc. For example, after a real world player wins a jackpot, 3D information about the player's actions may be stored. The casino system may then introduce a virtual player into the AR/VR casino and models the player on a real world player that won \$10,000 two months ago. As a result, the casino may appear busier, luckier, exciting, etc., to current players. The virtual players may include 3D animations that may be predetermined and/or dynamically generated. Cameras or sensors, e.g., associated with the VR/AR system and/or within a real world casino environment, may also be used to make models and recordings of real player actions, which can be used to generate more realistic virtual players.

For example, a VR system may include a headset as well as sensors to track the player movement of hands, body, etc. The VR system may also record the player's voice, eye movement, and/or other behaviors. 3D animations of the player and/or player behaviors may be selectively recorded for future use. In some embodiments, personally identifiable aspects of a recorded player may be anonymized, as needed or desired, e.g., as may be required by a particular jurisdiction and/or to facilitate player acceptance. For example, the system may notice a recorded player is a female of a certain age range and may replace the player's recorded voice with a simulated voice corresponding to the player's gender and/or age range. The system might record and store recordings of any number of common activities, behaviors, and/or reactions, such as small wins, big wins, near wins, happy players, players looking for a machine, walking around, etc. Many types of cameras, gloves (e.g., finger tracking and/or motion tracking gloves), clothing and/or sensors may be used to capture or track body motion.

In some examples, the system can add or remove virtual players to and from the AR/VR casino environment. For example, it may be desirable for the casino that the EGMs look busy by making sure seats are occupied by virtual players and empty seats are minimized or reduced, and it

may also be desirable for a player to find an empty EGM. In some embodiments, a host system can monitor the movements of players in the virtual environment and have virtual players get up and leave EGMs based upon a maximum occupancy target, a free seat target, or based on other criteria, such as a live player approaching an EGM or bank of EGMs. The host system may predict which virtual player should get up and leave by understanding and predicting a behavior of the real virtual player. For example, when a player known to be a high roller video poker player walks towards the high roller video poker area, the host system may predict that this player will want to play a high roller video poker machine and may cause one or more of the virtual players to get up and walk away leaving the target EGM empty for the live player. In another embodiment, the live player may prefer to play in a less crowded environment, and the host system may have multiple virtual players leave so the live player can play without sitting next to anyone else. In another embodiment, the system may predict that the live player prefers playing multiple EGMs at the same time in the high limit room and may have multiple virtual players get up and leave the high limit room to ensure the real virtual player has access to a sufficient number of adjacent EGMs to play.

The host system may use different algorithms and/or models to help associated the virtual players with various actions. For example, in some embodiments, the host system may target a certain frequency of win, such as every minute, and assign virtual players to win at the targeted win frequency. In another embodiment, the host system may a certain amount of wins per unit of time and assigns virtual players accordingly. The host system can assign these players to target any number of occurrences, such as amount of win, frequency of win, type of win (e.g., bonus, royal flush, free spin, sports wager, etc.), occupancy targets (such as maintaining a particular number or range of players in the environment, or a particular number or range of players per unit area, e.g., 2 players per 100 square feet). These occurrences and combinations thereof can be fixed or change over time. For example, occupancy targets may be adjusted higher on a Friday and Saturday night, and lower on weeknights.

In some embodiments, the same virtual player in a shared virtual environment (SVE) may have different appearances and/or behaviors for different live players, with different experiences in the same SVE tailored for different players. For example, the appearances, age, attire, and/or behavior could vary per targeted player. For example, for a target player that is young and active, the virtual players may be in a younger demographic and shown to have behaviors such as celebrating loudly, dancing, drinking, singing and socializing with other virtual or real players. Meanwhile, for another target player that is a high roller and reserved may see virtual players in the same SVE dressed in work casual clothing and socializing and celebrating in a more reserved manner. The appearances and behaviors of the virtual players could vary and be targeted by any number of factors, including demographic (e.g., age, nationality, etc.), clothing, personality, perceived income, association with a particular group (e.g., dog lovers, motorcycle fans, etc.), social introversion and/or extroversion, physical appearance (height, weight, hair color, etc.), use of certain products based on player preferences, casino promotions, etc., gaming products and/or features such as EGMs, button panels, casino chips, game types on casino products (video poker, spinning reel slots, etc.), and/or non-gaming items such as coffee cups, purses, cell phones, accessories, etc.

In some embodiments, virtual players may be used to market products and/or services. For example, appearances and behaviors of virtual players may be customized to employ product placement, advertising on clothing, etc. Examples may include holding a branded coffee cup to promote an onsite coffee shop, athletic gear and post-workout appearance to promote an onsite fitness center, swim gear and towels to promote a pool, show tickets and souvenirs to promote a real or virtual showroom, food and drink items, shopping bags and retail items, and/or clothing or objects with brand logos to promote various goods and services.

In some embodiments, virtual persons representing casino employees may also be present in the SVE. The virtual employees may be associated with actual employees and/or may be system controlled. In some examples, the virtual employees may interact with players to greet, congratulate, assist or inform players of products, services or promotions. High rollers in physical casinos may also be assigned a virtual casino host who may escort the player around the casino. In another embodiment, virtual wait staff may be available around the casino to offer players virtual drinks, food, cigarettes, etc. In some embodiments, a real employee may take control of a system controlled virtual employee, for example if a player needs additional assistance or becomes unsatisfied with an experience. Players may tip virtual employees for customer service, which may create improved interactions over time between the virtual employee and the player. For example, a virtual casino employee may recognize frequent players who are good tippers, and refer to them by name, and/or in the case of casino wait staff, may offer them a preferred drink, etc. Alternatively, or in addition, players who are good tippers may be assigned to be served by real virtual casino staff, whereas players who aren't good tippers, or don't visit the casino as frequently, may only be served by purely virtual employees. In some examples, the system may collect tips given to purely virtual employees and distribute them to the casino itself, or may distribute the tips in a pool with the other real casino employees who are helping players on the virtual casino floor.

Before discussing these and other embodiments in greater detail, reference will be made to an example of a gaming system for implementing embodiments disclosed herein. In this regard, FIG. 1 illustrates a gaming system 10 including a plurality of gaming devices 100 is illustrated. As discussed above, the gaming devices 100 may be one type of a variety of different types of gaming devices, such as electronic gaming machines (EGMs), mobile gaming devices, or other devices, for example. The gaming system 10 may be located, for example, on the premises of a gaming establishment, such as a casino. The gaming devices 100, which are typically situated on a casino floor, may be in communication with each other and/or at least one central controller 40 through a data communication network 50 that may include a remote communication link. The data communication network 50 may be a private data communication network that is operated, for example, by the gaming facility that operates the gaming devices 100. Communications over the data communication network 50 may be encrypted for security. The central controller 40 may be any suitable server or computing device which includes at least one processing circuit and at least one memory or storage device. Each gaming device 100 may include a processing circuit that transmits and receives events, messages, commands or any other suitable data or signal between the gaming device 100 and the central controller 40. The gaming device processing

circuit is operable to execute such communicated events, messages or commands in conjunction with the operation of the gaming device 100. Moreover, the processing circuit of the central controller 40 is configured to transmit and receive events, messages, commands or any other suitable data or signal between the central controller 40 and each of the individual gaming devices 100. In some embodiments, one or more of the functions of the central controller 40 may be performed by one or more gaming device processing circuits. Moreover, in some embodiments, one or more of the functions of one or more gaming device processing circuits as disclosed herein may be performed by the central controller 40.

A wireless access point 60 provides wireless access to the data communication network 50. The wireless access point 60 may be connected to the data communication network 50 as illustrated in FIG. 1, and/or may be connected directly to the central controller 40 or another server connected to the data communication network 50.

A player tracking server 45 may also be connected through the data communication network 50. The player tracking server 45 may manage a player tracking account that tracks the player's gameplay and spending and/or other player preferences and customizations, manages loyalty awards for the player, manages funds deposited or advanced on behalf of the player, and other functions. Player information managed by the player tracking server 45 may be stored in a player information database 47.

As further illustrated in FIG. 1, the gaming system 10 may include a ticket server 90 that is configured to print and/or dispense wagering tickets. The ticket server 90 may be in communication with the central controller 40 through the data communication network 50. Each ticket server 90 may include a processing circuit that transmits and receives events, messages, commands or any other suitable data or signal between the ticket server 90 and the central controller 40. The ticket server 90 processing circuit may be operable to execute such communicated events, messages or commands in conjunction with the operation of the ticket server 90. Moreover, in some embodiments, one or more of the functions of one or more ticket server 90 processing circuits as disclosed herein may be performed by the central controller 40.

The gaming devices 100 communicate with one or more elements of the gaming system 10 to coordinate providing wagering games and other functionality. For example, in some embodiments, the gaming device 100 may communicate directly with the ticket server 90 over a wireless interface 62, which may be a WiFi link, a Bluetooth link, a near field communications (NFC) link, etc. In other embodiments, the gaming device 100 may communicate with the data communication network 50 (and devices connected thereto, including other gaming devices 100) over a wireless interface 64 with the wireless access point 60. The wireless interface 64 may include a WiFi link, a Bluetooth link, an NFC link, etc. In still further embodiments, the gaming devices 100 may communicate simultaneously with both the ticket server 90 over the wireless interface 66 and the wireless access point 60 over the wireless interface 64. Some embodiments provide that gaming devices 100 may communicate with other gaming devices over a wireless interface 64. In these embodiments, wireless interface 62, wireless interface 64 and wireless interface 66 may use different communication protocols and/or different communication resources, such as different frequencies, time slots, spreading codes, etc.

The wireless interfaces 62, 66 allow a plurality of virtual reality (VR) and/or augmented reality (AR) devices, referred to herein as VR/AR devices 200, to coordinate the generation and rendering of VR and/or AR images to the player. As used herein, VR/AR devices 200 may include VR and/or AR functionality, as desired. In some embodiments, the gaming system 10 includes a VR/AR controller 114. The VR/AR controller 114 may be a computing system that communicates through the data communication network 50 with the EGMs 100 and the VR devices 200 to coordinate the generation and rendering of virtual images to one or more players using the VR devices 200. The VR/AR controller 114 may be implemented within or separately from the central controller 40.

In some embodiments, the VR/AR controller 114 may coordinate the generation and display of the virtual images of the same virtual object to more than one player by more than one VR/AR device 200. As described in more detail below, this may enable multiple players to interact with the same virtual object together in real time. This feature can be used to provide a shared multiplayer experience to multiple players at the same time.

Moreover, in some embodiments, the VR/AR controller 114 may coordinate the generation and display of the same virtual object to players at different physical locations, as will be described in more detail below.

The VR/AR controller 114 may store a three-dimensional wireframe map of a gaming area, such as a casino floor, and may provide the three-dimensional wireframe map to the VR/AR devices 200. The wireframe map may store various information about EGMs in the gaming area, such as the identity, type and location of various types of EGMs. The three-dimensional wireframe map may enable a VR/AR device 200 to more quickly and accurately determine its position and/or orientation within the gaming area, and also may enable the VR/AR device 200 to assist the player in navigating the gaming area while using the VR/AR device 200. The generation of three-dimensional wireframe maps is described in more detail below.

In some embodiments, at least some processing of virtual images and/or objects that are rendered by the VR devices 200 may be performed by the VR/AR controller 114, thereby offloading at least some processing requirements from the VR devices 200.

Embodiments herein may include different types of gaming devices. One example of a gaming device includes a gaming device 100 that can use gesture, voice, and/or touch-based inputs according to various embodiments is illustrated in FIGS. 2A, 2B, and 2C in which FIG. 2A is a perspective view of a gaming device 100 illustrating various physical features of the device, FIG. 2B is a functional block diagram that schematically illustrates an electronic relationship of various elements of the gaming device 100, and FIG. 2C illustrates various functional modules that can be stored in a memory device of the gaming device 100. The embodiments shown in FIGS. 2A to 2C are provided as examples for illustrative purposes only. It will be appreciated that gaming devices may come in many different shapes, sizes, layouts, form factors, and configurations, and with varying numbers and types of input and output devices, and that embodiments are not limited to the particular gaming device structures described herein.

Gaming devices 100 typically include a number of standard features, many of which are illustrated in FIGS. 2A and 2B. For example, referring to FIG. 2A, a gaming device 100 (which is an EGM 160 in this embodiment) may include a support structure, housing 105 (e.g., cabinet) which provides

support for a plurality of displays, inputs, outputs, controls and other features that enable a player to interact with the gaming device 100.

The gaming device 100 illustrated in FIG. 2A includes a number of display devices, including a primary display device 116 located in a central portion of the housing 105 and a secondary display device 118 located in an upper portion of the housing 105. A plurality of game components 155 are displayed on a display screen 117 of the primary display device 116. It will be appreciated that one or more of the display devices 116, 118 may be omitted, or that the display devices 116, 118 may be combined into a single display device. The gaming device 100 may further include a player tracking display 142, a credit display 120, and a bet display 122. The credit display 120 displays a player's current number of credits, cash, account balance or the equivalent. The bet display 122 displays a player's amount wagered. Locations of these displays are merely illustrative as any of these displays may be located anywhere on the gaming device 100.

The player tracking display 142 may be used to display a service window that allows the player to interact with, for example, their player loyalty account to obtain features, bonuses, comps, etc. In other embodiments, additional display screens may be provided beyond those illustrated in FIG. 2A. In some embodiments, one or more of the player tracking display 142, the credit display 120 and the bet display 122 may be displayed in one or more portions of one or more other displays that display other game related visual content. For example, one or more of the player tracking display 142, the credit display 120 and the bet display 122 may be displayed in a picture in a picture on one or more displays.

The gaming device 100 may further include a number of input devices 130 that allow a player to provide various inputs to the gaming device 100, either before, during or after a game has been played. The gaming device may further include a game play initiation button 132 and a cashout button 134. The cashout button 134 is utilized to receive a cash payment or any other suitable form of payment corresponding to a quantity of remaining credits of a credit display.

In some embodiments, one or more input devices of the gaming device 100 are one or more game play activation devices that are each used to initiate a play of a game on the gaming device 100 or a sequence of events associated with the gaming device 100 following appropriate funding of the gaming device 100. The example gaming device 100 illustrated in FIGS. 2A and 2B includes a game play activation device in the form of a game play initiation button 132. It should be appreciated that, in other embodiments, the gaming device 100 begins game play automatically upon appropriate funding rather than upon utilization of the game play activation device.

In some embodiments, one or more input device 130 of the gaming device 100 may include wagering or betting functionality. For example, a maximum wagering or betting function may be provided that, when utilized, causes a maximum wager to be placed. Another such wagering or betting function is a repeat the bet device that, when utilized, causes the previously-placed wager to be placed. A further such wagering or betting function is a bet one function. A bet is placed upon utilization of the bet one function. The bet is increased by one credit each time the bet one device is utilized. Upon the utilization of the bet one function, a quantity of credits shown in a credit display (as described

below) decreases by one, and a number of credits shown in a bet display (as described below) increases by one.

In some embodiments, as shown in FIG. 2B, the input device(s) 130 may include and/or interact with additional components, such as gesture sensors 156 for gesture input devices, and/or a touch-sensitive display that includes a digitizer 152 and a touchscreen controller 154 for touch input devices, as disclosed herein. The player may interact with the gaming device 100 by touching virtual buttons on one or more of the display devices 116, 118, 140. Accordingly, any of the above-described input devices, such as the input device 130, the game play initiation button 132 and/or the cashout button 134 may be provided as virtual buttons or regions on one or more of the display devices 116, 118, 140.

Referring briefly to FIG. 2B, operation of the primary display device 116, the secondary display device 118 and the player tracking display 142 may be controlled by a video controller 30 that receives video data from a processing circuit 12 or directly from a memory device 14 and displays the video data on the display screen. The credit display 120 and the bet display 122 are typically implemented as simple liquid crystal display (LCD) or light emitting diode (LED) displays that display a number of credits available for wagering and a number of credits being wagered on a particular game. Accordingly, the credit display 120 and the bet display 122 may be driven directly by the processing circuit 12. In some embodiments however, the credit display 120 and/or the bet display 122 may be driven by the video controller 30.

Referring again to FIG. 2A, the display devices 116, 118, 140 may include, without limitation: a cathode ray tube, a plasma display, an LCD, a display based on LEDs, a display based on a plurality of organic light-emitting diodes (OLEDs), a display based on polymer light-emitting diodes (PLEDs), a display based on a plurality of surface-conduction electron-emitters (SEDs), a display including a projected and/or reflected image, or any other suitable electronic device or display mechanism. In certain embodiments, as described above, the display devices 116, 118, 140 may include a touch-screen with an associated touchscreen controller 154 and digitizer 152. The display devices 116, 118, 140 may be of any suitable size, shape, and/or configuration. The display devices 116, 118, 140 may include flat or curved display surfaces.

The display devices 116, 118, 140 and video controller 30 of the gaming device 100 are generally configured to display one or more game and/or non-game images, symbols, and indicia. In certain embodiments, the display devices 116, 118, 140 of the gaming device 100 are configured to display any suitable visual representation or exhibition of the movement of objects; dynamic lighting; video images; images of people, characters, places, things, and faces of cards; and the like. In certain embodiments, the display devices 116, 118, 140 of the gaming device 100 are configured to display one or more virtual reels, one or more virtual wheels, and/or one or more virtual dice. In other embodiments, certain of the displayed images, symbols, and indicia are in mechanical form. That is, in these embodiments, the display device 116, 118, 140 includes any electromechanical device, such as one or more rotatable wheels, one or more reels, and/or one or more dice, configured to display at least one or a plurality of game or other suitable images, symbols, or indicia.

The gaming device 100 also includes various features that enable a player to deposit credits in the gaming device 100 and withdraw credits from the gaming device 100, such as in the form of a payout of winnings, credits, etc. For example, the gaming device 100 may include a bill/ticket

dispenser 136, a bill/ticket acceptor 128, and a coin acceptor 126 that allows the player to deposit coins into the gaming device 100.

As illustrated in FIG. 2A, the gaming device 100 may also include a currency dispenser 137 that may include a note dispenser configured to dispense paper currency and/or a coin generator configured to dispense coins or tokens in a coin payout tray.

The gaming device 100 may further include one or more speakers 150 controlled by one or more sound cards 28 (FIG. 2B). The gaming device 100 illustrated in FIG. 2A includes a pair of speakers 150. In other embodiments, additional speakers, such as surround sound speakers, may be provided within or on the housing 105. Moreover, the gaming device 100 may include built-in seating with integrated headrest speakers.

In various embodiments, the gaming device 100 may generate dynamic sounds coupled with attractive multimedia images displayed on one or more of the display devices 116, 118, 140 to provide an audio-visual representation or to otherwise display full-motion video with sound to attract players to the gaming device 100 and/or to engage the player during gameplay. In certain embodiments, the gaming device 100 may display a sequence of audio and/or visual attraction messages during idle periods to attract potential players to the gaming device 100. The videos may be customized to provide any appropriate information.

The gaming device 100 may further include a card reader 138 that is configured to read magnetic stripe cards, such as player loyalty/tracking cards, chip cards, and the like. In some embodiments, a player may insert an identification card into a card reader of the gaming device. In some embodiments, the identification card is a smart card having a programmed microchip or a magnetic strip coded with a player's identification, credit totals (or related data) and other relevant information. In other embodiments, a player may carry a portable device, such as a cell phone, a radio frequency identification tag or any other suitable wireless device, which communicates a player's identification, credit totals (or related data) and other relevant information to the gaming device. In some embodiments, money may be transferred to a gaming device through electronic funds transfer. When a player funds the gaming device, the processing circuit determines the amount of funds entered and displays the corresponding amount on the credit or other suitable display as described above.

In some embodiments, the gaming device 100 may include an electronic payout device or module configured to fund an electronically recordable identification card or smart card or a bank or other account via an electronic funds transfer to or from the gaming device 100.

FIG. 2B is a block diagram that illustrates logical and functional relationships between various components of a gaming device 100. It should also be understood that components described in FIG. 2B may also be used in other computing devices, as desired, such as mobile computing devices for example. As shown in FIG. 2B, the gaming device 100 may include a processing circuit 12 that controls operations of the gaming device 100. Although illustrated as a single processing circuit, multiple special purpose and/or general purpose processors and/or processor cores may be provided in the gaming device 100. For example, the gaming device 100 may include one or more of a video processor, a signal processor, a sound processor and/or a communication controller that performs one or more control functions within the gaming device 100. The processing circuit 12 may be variously referred to as a "controller," "microcon-

troller," "microprocessor" or simply a "computer." The processor may further include one or more application-specific integrated circuits (ASICs).

Various components of the gaming device 100 are illustrated in FIG. 2B as being connected to the processing circuit 12. It will be appreciated that the components may be connected to the processing circuit 12 through a system bus 151, a communication bus and controller, such as a universal serial bus (USB) controller and USB bus, a network interface, or any other suitable type of connection.

The gaming device 100 further includes a memory device 14 that stores one or more functional modules 20. Various functional modules 20 of the gaming device 100 will be described in more detail below in connection with FIG. 2D.

The memory device 14 may store program code and instructions, executable by the processing circuit 12, to control the gaming device 100. The memory device 14 may also store other data such as image data, event data, player input data, random or pseudo-random number generators, pay-table data or information and applicable game rules that relate to the play of the gaming device. The memory device 14 may include random access memory (RAM), which can include non-volatile RAM (NVRAM), magnetic RAM (ARAM), ferroelectric RAM (FeRAM) and other forms as commonly understood in the gaming industry. In some embodiments, the memory device 14 may include read only memory (ROM). In some embodiments, the memory device 14 may include flash memory and/or EEPROM (electrically erasable programmable read only memory). Any other suitable magnetic, optical and/or semiconductor memory may operate in conjunction with the gaming device disclosed herein.

The gaming device 100 may further include a data storage 22, such as a hard disk drive or flash memory. The data storage 22 may store program data, player data, audit trail data or any other type of data. The data storage 22 may include a detachable or removable memory device, including, but not limited to, a suitable cartridge, disk, CD ROM, Digital Video Disc ("DVD") or USB memory device.

The gaming device 100 may include a communication adapter 26 that enables the gaming device 100 to communicate with remote devices over a wired and/or wireless communication network, such as a local area network (LAN), wide area network (WAN), cellular communication network, or other data communication network. The communication adapter 26 may further include circuitry for supporting short range wireless communication protocols, such as Bluetooth and/or NFC that enable the gaming device 100 to communicate, for example, with a mobile communication device operated by a player.

The gaming device 100 may include one or more internal or external communication ports that enable the processing circuit 12 to communicate with and to operate with internal or external peripheral devices, such as eye tracking devices, position tracking devices, cameras, accelerometers, arcade sticks, bar code readers, bill validators, biometric input devices, bonus devices, button panels, card readers, coin dispensers, coin hoppers, display screens or other displays or video sources, expansion buses, information panels, keypads, lights, mass storage devices, microphones, motion sensors, motors, printers, reels, Small Computer System Interface ("SCSI") ports, solenoids, speakers, thumb drives, ticket readers, touch screens, trackballs, touchpads, wheels, and wireless communication devices. In some embodiments, internal or external peripheral devices may communicate with the processing circuit through a USB hub (not shown) connected to the processing circuit 12.

In some embodiments, the gaming device 100 may include a sensor, such as a camera 127, in communication with the processing circuit 12 (and possibly controlled by the processing circuit 12) that is selectively positioned to acquire an image of a player actively using the gaming device 100 and/or the surrounding area of the gaming device 100. In one embodiment, the camera 127 may be configured to selectively acquire still or moving (e.g., video) images and may be configured to acquire the images in either an analog, digital or other suitable format. The display devices 116, 118, 140 may be configured to display the image acquired by the camera 127 as well as display the visible manifestation of the game in split screen or picture-in-picture fashion. For example, the camera 127 may acquire an image of the player and the processing circuit 12 may incorporate that image into the primary and/or secondary game as a game image, symbol or indicia.

Various functional modules of that may be stored in a memory device 14 of a gaming device 100 are illustrated in FIG. 2C. Referring to FIG. 2C, the gaming device 100 may include in the memory device 14 a game module 20A that includes program instructions and/or data for operating a hybrid wagering game as described herein. The gaming device 100 may further include a player tracking module 20B, an electronic funds transfer module 20C, an input device interface 20D, an audit/reporting module 20E, a communication module 20F, an operating system kernel 20G and a random number generator 20H. The player tracking module 20B keeps track of the play of a player. The electronic funds transfer module 20C communicates with a back end server or financial institution to transfer funds to and from an account associated with the player. The input device interface 20D interacts with input devices, such as the input device 130, as described in more detail below. The communication module 20F enables the gaming device 100 to communicate with remote servers and other gaming devices using various secure communication interfaces. The operating system kernel 20G controls the overall operation of the gaming device 100, including the loading and operation of other modules. The random number generator 20H generates random or pseudorandom numbers for use in the operation of the hybrid games described herein.

In some embodiments, a gaming device 100 includes a personal device, such as a desktop computer, a laptop computer, a mobile device, a tablet computer or computing device, a personal digital assistant (PDA), or other portable computing devices. In some embodiments, the gaming device 100 may be operable over a wireless network, such as part of a wireless gaming system. In such embodiments, the gaming machine may be a hand-held device, a mobile device or any other suitable wireless device that enables a player to play any suitable game at a variety of different locations. It should be appreciated that a gaming device or gaming machine as disclosed herein may be a device that has obtained approval from a regulatory gaming commission or a device that has not obtained approval from a regulatory gaming commission.

For example, referring to FIG. 2D, a gaming device 100 (which is a mobile gaming device 170 in this embodiment) may be implemented as a handheld device including a compact housing 105 on which is mounted a touchscreen display device 116 including a digitizer 152. As described in greater detail with respect to FIG. 3 below, one or more input devices 130 may be included for providing functionality of for embodiments described herein. A camera 127 may be provided in a front face of the housing 105. The housing 105 may include one or more speakers 150. In the gaming device

100, various input buttons described above, such as the cashout button, gameplay activation button, etc., may be implemented as soft buttons on the touchscreen display device 116 and/or input device 130. In this embodiment, the input device 130 is integrated into the touchscreen display device 116, but it should be understood that the input device may also, or alternatively, be separate from the display device 116. Moreover, the gaming device 100 may omit certain features, such as a bill acceptor, a ticket generator, a coin acceptor or dispenser, a card reader, secondary displays, a bet display, a credit display, etc. Credits can be deposited in or transferred from the gaming device 100 electronically.

FIG. 2E illustrates a standalone gaming device 100 (which is an EGM 160 in this embodiment) having a different form factor from the EGM 160 illustrated in FIG. 2A. In particular, the gaming device 100 is characterized by having a large, high aspect ratio, curved primary display device 116 provided in the housing 105, with no secondary display device. The primary display device 116 may include a digitizer 152 to allow touchscreen interaction with the primary display device 116. The gaming device 100 may further include a player tracking display 142, an input device 130, a bill/ticket acceptor 128, a card reader 138, and a bill/ticket dispenser 136. The gaming device 100 may further include one or more cameras 127 to enable facial recognition and/or motion tracking.

FIG. 2F illustrates a virtual reality (VR) viewer 200A implemented as a 3D headset including a pair of displays 218 on which images of virtual objects may be displayed. The viewer 200A includes a head-wearable frame 202, with the displays 218 coupled to the frame 202 to position the display device in a field of view of user wearing the viewer 200A. Different stereoscopic images may be displayed on the displays 218 to create an appearance of depth. The VR viewer 200A may include a plurality of sensors 220 that the device uses to determine a position, orientation, and/or movement of the viewer 200A, which may be used to determine a position, orientation, and/or direction of movement within an SVE.

The viewer 200A may further include other sensors, such as a gyroscopic sensor, a GPS sensor, one or more accelerometers, and/or other sensors that allow the viewer 200A to determine its position and orientation in space. In some embodiments, the viewer 200A may include one or more cameras that allow the viewer 200A to determine its position and/or orientation in space using visual simultaneous localization and mapping (VSLAM). viewer 200A may further include one or more microphones and/or speakers that allow the user to interact audially with the device.

In some embodiments, a viewer may also include semi-transparent lenses that allow the user to see both the real world as well as the 3D image rendered on the lenses, e.g., to provide an augmented reality (AR) experience. The viewer may also include additional cameras or other sensors to obtain a live video signal for building a 3D model of the space around the user. The viewer may also generate a 3D image of an object to display to the user that takes into account the real world objects around the user and allows the user to interact with the 3D object.

Referring to FIG. 2G, an augmented reality (AR) viewer 200B may be implemented as a pair of glasses including a transparent prismatic display 222 that displays an image to a single eye of the user. Such a device may be capable of displaying images to the user while allowing the user to see the world around the user, and as such can be used as an AR device.

In other embodiments, a VR and/or AR viewer may be implemented using a virtual retinal display device that raster scans an image directly onto the retina of the user. In still further embodiments, a VR and/or AR viewer may be implemented using a mobile wireless device, such as the mobile gaming device 170 of FIG. 2D above, a mobile telephone, a tablet computing device, and/or a personal digital assistant, etc.

Although illustrated as certain gaming devices, such as electronic gaming machines (EGMs), mobile gaming devices, VR/AR headsets, etc., functions and/or operations as described herein may also include wagering stations that may include electronic game tables, conventional game tables including those involving cards, dice and/or roulette, and/or other wagering stations such as sports book stations, video poker games, skill-based games, virtual casino-style table games, or other casino or non-casino style games. Further, gaming devices according to embodiments herein may be implemented using other computing devices and mobile devices, such as smart phones, tablets, and/or personal computers, among others.

FIG. 3A illustrates, in plain view, an example map 338 of a gaming area 340. The gaming area 340 may, for example, be a casino floor. The map 338 shows the location of a plurality of EGMS 100 within the gaming area 340. As will be appreciated, the locations of the EGMS 100 within a gaming area 340 are generally fixed, although EGMS may be relocated from time to time, such as when new EGMS are introduced, to create new traffic flow patterns within the gaming area 340, to feature or highlight certain games, etc. As noted above, in order to assist the operation of the VR devices 200, the VR/AR controller 114 may store a three-dimensional wireframe map of the gaming area 340, and may provide the three dimensional wireframe map to the VR viewers 200.

An example of a wireframe map 342 for an SVE is shown in FIG. 3B. The wireframe map 342 is a three-dimensional model of the gaming area 340. As shown in FIG. 3B, the wireframe map 342 includes wireframe models 344 that may correspond to the EGMS 100 that are physically in the gaming area 340. The wireframe models 344 may also be entirely or partially virtual, e.g., existing only in the wireframe model 344 for the SVE. The wireframe models 344 may be pregenerated to correspond to various EGM form factors, such as single display EGMS, mechanical slot EGMS, dual display EGMS, etc. The pregenerated models may then be placed into the wireframe map 342, for example, by a designer or other personnel. The wireframe map 342 may be updated at any time. For example, in an example where the wireframe map 342 corresponds to a real-world gaming area 340, the wireframe map 342 may be updated whenever the physical location of EGMS in the gaming area 340 is changed.

In some embodiments, the wireframe map 342 may be generated automatically using a VR/AR device 200, such as a 3D headset, that is configured to perform a three-dimensional depth scan of its surroundings and generate a three-dimensional model based on the scan results. Thus, for example, an operator using a VR/AR device 200 may perform a walkthrough of the gaming area 340 while the VR/AR device 200 builds the 3D map of the gaming area.

The three-dimensional wireframe map 342 may enable a VR/AR device 200 to more quickly and accurately determine its position and/or orientation within the gaming area. For example, a VR/AR device 200 may determine its location within the gaming area 340 using one or more position/orientation sensors. The VR/AR device 200 then

builds a three-dimensional map of its surroundings using depth scanning, and compares its sensed location relative to objects within the generated three dimensional map with an expected location based on the location of corresponding objects within the wireframe map 342. The VR/AR device 200 may calibrate or refine its position/orientation determination by comparing the sensed position of objects with the expected position of objects based on the wireframe map 342. Moreover, in an AR implementation, the VR/AR device 200 can be aware of objects or destinations within the gaming area 340 that it has not itself scanned, because the VR/AR device 200 has access to the wireframe map 342 of the entire gaming area 340. Processing requirements on the VR/AR device 200 may also be reduced because the wireframe map 342 is already available to the VR/AR device 200.

In some embodiments, the wireframe map 342 may store various information about EGMS in the gaming area, such as the identity, type, appearance, manufacturer, model, brand, color, texture, orientation and location of various types of EGMS, the locations of exits, bathrooms, courtesy desks, cashiers, ATMs, ticket redemption machines, etc. Such information may be used by a VR/AR device 200 to help the user navigate the gaming area. For example, if a user desires to find a destination within the gaming area, the user may ask the VR/AR device 200 for directions using a built-in microphone and voice recognition function in the VR/AR device 200 or use other hand gestures or eye/gaze controls tracked by the VR/AR device 200 (instead of or in addition to voice control). The VR/AR device 200 may process the request to identify the destination, and then may display a virtual object, such as a virtual path on the ground, virtual arrow, virtual sign, etc., to help the user to find the destination. In some embodiments, for example, the VR/AR device 200 may display a halo or glow around the destination to highlight it for the user, or have virtual 3D sounds coming from it so players could more easily find the machine.

According to some embodiments, a user of a VR/AR device 200 may use the VR/AR device 200 to obtain information about players and/or EGMS on a casino gaming floor. The information may be displayed to the user on the VR/AR device 200 in a number of different ways such as by displaying images on the VR/AR device 200 that appear to be three-dimensional or two-dimensional elements of the scene as viewed through the VR/AR device 200. In general, the type and/or amount of data that is displayed to the user may depend on what type of user is using the VR/AR device 200 and, correspondingly, what level of permissions or access the user has. For example, a VR/AR device 200 may be operated in one of a number of modes, such as a player mode, an observer mode or an operator mode. In a player mode, the VR/AR device 200 may be used to display information about particular EGMS on a casino floor. The information may be generic information about an EGM or may be customized information about the EGM based on the identity or preferences of the user of the VR/AR device 200. In an observer mode, the VR/AR device 200 may be used to display information about particular EGMS on a casino floor or information about players of EGMS on the casino floor. In an operator mode, the VR/AR device 200 may also be used to display information about particular EGMS on a casino floor or information about players of EGMS on the casino floor, but the information may be different or more extensive than the information displayed to an observer.

FIGS. 4A and 4B are views of a shared virtual environment (SVE) 404 corresponding to fields of views (FOVs) of a plurality of players wearing head-mounted virtual reality

devices 400A-400B, according to some embodiments. In this embodiment a real-time environmental model of the SVE 404 is provided, including a plurality of virtual persons 406 and a plurality of virtual gaming devices 408.

As shown by FIG. 4A, display data corresponding to the SVE 404 is transmitted to a first player device 400A worn by a first player. The first display data includes user display data that causes a display device 402A in the first player device 400A to render a portion of the SVE 404 based on a virtual orientation of the first player device 400A and a virtual location of the first player in the SVE 404. In the view shown by FIG. 4A, the portion of the SVE 404 is displayed as a 3D environment of a casino floor, with virtual persons 406, virtual gaming devices 408 arranged on the virtual casino floor. The virtual persons 406 may correspond to other real-world players, e.g., other players with their own VR devices, and/or system controlled players, e.g., virtual players that are controlled by a set of environmental rules, artificial intelligence, etc., to simulate a real-world casino environment. In some embodiments, the SVE 404 may also correspond to a real world environment, e.g., to a real-world casino floor with a similar or identical layout, and may include a full or partial floorplan corresponding to a floorplan of the real world environment, with elements such as virtual gaming devices 408 fully or partially corresponding to actual gaming device on the real-world casino floor. In other embodiments, the SVE 404 may be partially or entirely artificial, with little or no correspondence to a real world location, as desired.

Based on a player preference associated with the first player, an appearance and/or behavior of different virtual persons 406 may be modified such that the virtual persons appear and/or behave differently for different players interacting with the SVE 404. For example, FIG. 4A illustrates an SVE 404 including three virtual persons 406-1-406-3 and three virtual gaming devices 408-1-408-3 in field of view of a first display device 402A associated with a first player interacting with the SVE 404. In this example, based on the player's preferences or other factors, a presentation 410 of each virtual person 406 may be modified, i.e., a first virtual person 406-1 may have a presentation 410A-1, a second virtual person 406-2 may have a presentation 410A-2, and so on. Each presentation 410A-1-410A-3 may include a number of modifications to the appearance and/or behavior of each respective virtual person 406-1-406-3. For example, each presentation 410A-1-410A-3 may include modifications to virtual apparel being worn by the respective virtual player 406-1-406-3, an apparent age of the respective virtual player 406-1-406-3, a wagering style of the respective virtual player 406-1-406-3 (e.g., aggressive, cautious, consistent, unpredictable, etc.). In some examples, each presentation 410A-1-410A-3 may include modifications to a game result reaction style of the respective virtual player 406-1-406-3 (e.g., quiet, lively, boisterous, etc.). For example, displaying the wagering style and/or game reaction style may include displaying a previously recorded behavior of another player, e.g., playing a wagering game, as the particular virtual person to better simulate realistic play styles and/or reactions to be displayed to the player viewing the virtual person. Likewise, the gaming devices 408-1-408-3 may have modified presentations 412A-1-412A-3 (e.g., different themes, appearances, styles, etc.) as well.

Subsets of virtual persons 406 may be associated with other players wearing a plurality of player devices, while different subsets of virtual persons 406 may include system-controlled virtual persons. For example, the virtual person 406-1 in FIGS. 4A and 4B is associated with another player

wearing a player device, while the virtual persons 406-2 and 406-3 in FIGS. 4A and 4B are system controlled virtual persons. The subsets of virtual persons 406 being displayed to different players from different locations and orientations in the SVE 404 may correspond to the players wearing the player devices 402.

As shown by FIG. 4B, display data corresponding to SVE 404 is also transmitted to a second player device 400B worn by a second player. The second display data includes user display data that causes a display device 402B in the second player device 400B to render a portion of the SVE 404 based on a virtual orientation of the second player device 400B and a virtual location of the second player in the second SVE 404B. In this example, the virtual orientation of the second player device 400B and the virtual location of the second player in the SVE 404 are similar to the virtual orientation of the first player device 400A and the virtual location of the first player in the SVE 404, so that the overall arrangements of the scenes being viewed by the first and second players are similar.

The portion of the SVE 404 in this example includes a plurality of virtual persons 406 and gaming devices 408 corresponding to the same virtual persons 406 and gaming devices 408 illustrated in FIG. 4A. In this example, however, based on a different player preference associated with the second player, an appearance and/or behavior of different virtual persons 406 may be modified such that the virtual persons appear and/or behave differently for the second player interacting with the SVE 404. For example, FIG. 4B illustrates an SVE 404 including the same three virtual persons 406-1-406-3 and the same three virtual gaming devices 408-1-408-3 in field of view of a second display device 402B associated with a second player interacting with the SVE 404. Based on the second player's preferences or other factors, a presentation 410 of each virtual person 406 may be modified to be different from the presentations 410 of FIG. 4A for the same virtual persons 406, i.e., the first virtual person 406-1 may have a different presentation 410B-1, the second virtual person 406-2 may have a different presentation 410B-2, and so on. As with FIG. 4A, each presentation 410B-1-410B-3 may include a number of modifications to the appearance and/or behavior of each respective virtual person 406-1-406-3, as discussed above. Likewise, the gaming devices 408-1-408-3 may have modified presentations 412B-1-412B-3 as well.

In this manner, the same SVE 404 may include the same basic elements, e.g., virtual persons 406, virtual gaming devices 408, etc., with different presentations for any number of different players, based on the individual player preferences or other factors.

Individual presentations for different virtual persons may be modified dynamically and/or in real time based on different criteria. For example, in one of the virtual persons 406 in the SVE 404 may correspond to a system-controlled virtual customer service representative. If the system determines that a player is interacting with the virtual customer service representative, the system may seamlessly transfer control of the virtual customer service representative from the system to a customer service representative who can then continue to directly interact with the player to provide customer service.

In some examples, a group of presentations 410 for virtual persons 406 and presentations 412 for gaming devices 408 may be synchronized for different groups of players interacting with the SVE 404, so that each player in a particular group has a shared experience within the SVE 404 with the same or similar presentations 410, 412 within the group,

while another group has a different experience within the SVE 404 with the same or similar presentations 410, 412 within the group but different from the presentations 410, 412 provided to other groups. For example,

As shown by FIGS. 5A-5C, an overhead view of a SVE 504 is illustrated showing movement of virtual persons 406 around the SVE 504. As discussed above, the floorplan of the SVE 504 may correspond to a real-world casino environment, to attract players interested in visiting the real world casino, and who may already be familiar with the real world casino. In some embodiments, aspects of the real world casino may be modified in the SVE 504. For example, the layout and decor of the SVE 504 may be modified for different players based on player preferences or other criteria to appear to be in a different time period, e.g., Las Vegas in the 1950s or 1970s, and may match the actual decor of the corresponding real world casino in that time period.

In some examples, virtual persons associated with players and/or system controlled virtual players may enter and exit the SVE 504 based on system and/or player virtual occupancy preferences, and/or other criteria. For example, as shown by FIG. 5A, a virtual first player 510 appears to a second player (i.e., virtual second player 518 corresponding to the second player) to be playing at a particular virtual gaming device 514 of a plurality of virtual gaming devices 408 in the SVE 504. In this example, the second player may have an associated occupancy preference and/or gaming style preference that include a preferred number and/or range of numbers of virtual persons in the SVE 504 and/or a preferred gaming device 408.

As shown by FIG. 5B, as the virtual second player 518 approaches the virtual first player 510, the system may determine that the second player wants to play at a specific virtual gaming device 514 occupied by the virtual first player 510. As a result, in FIG. 5C, the system causes the virtual first player 510 to leave the virtual gaming device 514 so that the second virtual player 518 can play at the virtual gaming device 514.

In addition, virtual persons 406, which may correspond to real-world players and/or system controlled virtual players, may enter and exit the SVE 504 over time. If the number of virtual persons 406 varies from the preferred number of virtual persons for the occupancy preference of the second player, the system may cause one or more virtual persons 406 to enter or exit the SVE 504. For example, as additional real or virtual players enter the SVE 504, the system may then cause another virtual person 406 to leave the SVE 504 based on the occupancy preference of the second player to maintain the number of virtual persons 406 in the SVE at the preferred number of virtual persons 406.

FIG. 6 is a flowchart illustrating operations 600 of systems/methods for facilitating embodiments described herein. The operations 600 may be performed by one or more processor circuits of one or more computing devices, such as any of the computing devices described herein, for example. The operations 600 may include providing, by a processor circuit, a real-time environmental model of a shared virtual environment (SVE) comprising a plurality of virtual persons and a plurality of virtual gaming devices (Block 602). Each SVE may include a plurality of virtual persons and a plurality of virtual gaming devices. For example, using the embodiment of FIGS. 4A-4C above, a real time model including the different SVEs 404, 504 may be provided.

The operations 600 may further include transmitting display data corresponding to the SVE to a first player device worn by a first player (Block 604). In this example,

the display data may include user display data that causes a display device in the first player device to render a portion of the SVE based on a virtual orientation of the first player device and a virtual location of the first player in the SVE, such as the SVEs 404, 504 in the example described above.

The operations 600 may further include determining, by the processor circuit, a player preference associated with the first player (Block 606) and, based on the player preference, modifying, by the processor circuit, one of an appearance 10 and a behavior of a first virtual person of the plurality of virtual persons in the SVE being displayed by the first player device (Block 608). For example, as discussed above with respect to FIGS. 4A and 4B, presentations 410 of virtual persons 406 may be modified, i.e., a first virtual person 406-1 may have a presentation 410A-1, a second virtual person 406-2 may have a presentation 410A-2, and so on, with each presentation 410A-1-410A-3 including a number of modifications to the appearance and/or behavior of each respective virtual person 406-1-406-3 (e.g., different from 15 presentations 410B-1-3 as shown by FIG. 4B).

Embodiments described herein may be implemented in various configurations for gaming devices 100, including but not limited to: (1) a dedicated gaming device, wherein the computerized instructions for controlling any games 25 (which are provided by the gaming device) are provided with the gaming device prior to delivery to a gaming establishment; and (2) a changeable gaming device, where the computerized instructions for controlling any games (which are provided by the gaming device) are download-30 able to the gaming device through a data network when the gaming device is in a gaming establishment. In some embodiments, the computerized instructions for controlling any games are executed by at least one central server, central controller or remote host. In such a “thin client” embodiment, the central server remotely controls any games (or other suitable interfaces) and the gaming device is utilized to display such games (or suitable interfaces) and receive one or more inputs or commands from a player. In another embodiment, the computerized instructions for controlling any games are communicated from the central server, central controller or remote host to a gaming device local processor and memory devices. In such a “thick client” embodiment, the gaming device local processor executes the communicated computerized instructions to control any games (or other suitable interfaces) provided to a player.

In some embodiments, a gaming device may be operated by a mobile device, such as a mobile telephone, tablet other mobile computing device. For example, a mobile device 45 may be communicatively coupled to a gaming device and may include a user interface that receives user inputs that are received to control the gaming device. The user inputs may be received by the gaming device via the mobile device.

In some embodiments, one or more gaming devices in a gaming system may be thin client gaming devices and one or more gaming devices in the gaming system may be thick client gaming devices. In another embodiment, certain functions of the gaming device are implemented in a thin client environment and certain other functions of the gaming device are implemented in a thick client environment. In one such embodiment, computerized instructions for controlling any primary games are communicated from the central server to the gaming device in a thick client configuration and computerized instructions for controlling any secondary games or bonus functions are executed by a central server in 60 a thin client configuration.

The present disclosure contemplates a variety of different gaming systems each having one or more of a plurality of

different features, attributes, or characteristics. It should be appreciated that a "gaming system" as used herein refers to various configurations of: (a) one or more central servers, central controllers, or remote hosts; (b) one or more gaming devices; and/or (c) one or more personal gaming devices, such as desktop computers, laptop computers, tablet computers or computing devices, PDAs, mobile telephones such as smart phones, and other mobile computing devices.

In certain such embodiments, computerized instructions for controlling any games (such as any primary or base games and/or any secondary or bonus games) displayed by the gaming device are executed by the central server, central controller, or remote host. In such "thin client" embodiments, the central server, central controller, or remote host remotely controls any games (or other suitable interfaces) displayed by the gaming device, and the gaming device is utilized to display such games (or suitable interfaces) and to receive one or more inputs or commands. In other such embodiments, computerized instructions for controlling any games displayed by the gaming device are communicated from the central server, central controller, or remote host to the gaming device and are stored in at least one memory device of the gaming device. In such "thick client" embodiments, the at least one processor of the gaming device executes the computerized instructions to control any games (or other suitable interfaces) displayed by the gaming device.

In some embodiments in which the gaming system includes: (a) a gaming device configured to communicate with a central server, central controller, or remote host through a data network; and/or (b) a plurality of gaming devices configured to communicate with one another through a data network, the data network is an internet or an intranet. In certain such embodiments, an internet browser of the gaming device is usable to access an internet game page from any location where an internet connection is available. In one such embodiment, after the internet game page is accessed, the central server, central controller, or remote host identifies a player prior to enabling that player to place any wagers on any plays of any wagering games. In one example, the central server, central controller, or remote host identifies the player by requiring a player account of the player to be logged into via an input of a unique username and password combination assigned to the player. It should be appreciated, however, that the central server, central controller, or remote host may identify the player in any other suitable manner, such as by validating a player tracking identification number associated with the player; by reading a player tracking card or other smart card inserted into a card reader (as described below); by validating a unique player identification number associated with the player by the central server, central controller, or remote host; or by identifying the gaming device, such as by identifying the MAC address or the IP address of the internet facilitator. In various embodiments, once the central server, central controller, or remote host identifies the player, the central server, central controller, or remote host enables placement of one or more wagers on one or more plays of one or more primary or base games and/or one or more secondary or bonus games, and displays those plays via the internet browser of the gaming device.

It should be appreciated that the central server, central controller, or remote host and the gaming device are configured to connect to the data network or remote communications link in any suitable manner. In various embodiments, such a connection is accomplished via: a conventional phone line or other data transmission line, a digital subscriber line

(DSL), a T-1 line, a coaxial cable, a fiber optic cable, a wireless or wired routing device, a mobile communications network connection (such as a cellular network or mobile internet network), or any other suitable medium. It should be appreciated that the expansion in the quantity of computing devices and the quantity and speed of internet connections in recent years increases opportunities for players to use a variety of gaming devices to play games from an ever-increasing quantity of remote sites. It should also be appreciated that the enhanced bandwidth of digital wireless communications may render such technology suitable for some or all communications, particularly if such communications are encrypted. Higher data transmission speeds may be useful for enhancing the sophistication and response of the display and interaction with players.

In the above-description of various embodiments, various aspects may be illustrated and described herein in any of a number of patentable classes or contexts including any new and useful process, machine, manufacture, or composition of matter, or any new and useful improvement thereof. Accordingly, various embodiments described herein may be implemented entirely by hardware, entirely by software (including firmware, resident software, micro-code, etc.) or by combining software and hardware implementation that may all generally be referred to herein as a "circuit," "module," "component," or "system." Furthermore, various embodiments described herein may take the form of a computer program product including one or more computer readable media having computer readable program code embodied thereon.

Any combination of one or more computer readable media may be used. The computer readable media may be a computer readable signal medium or a computer readable storage medium. A computer readable storage medium may be, for example, but not limited to, an electronic, magnetic, optical, electromagnetic, or semiconductor system, apparatus, or device, or any suitable combination of the foregoing. More specific examples (a non-exhaustive list) of the computer readable storage medium would include the following: a portable computer diskette, a hard disk, a random access memory (RAM), a read-only memory (ROM), an erasable programmable read-only memory (EPROM or Flash memory), an appropriate optical fiber with a repeater, a portable compact disc read-only memory (CD-ROM), an optical storage device, a magnetic storage device, or any suitable combination of the foregoing. In the context of this document, a computer readable storage medium may be any medium that can contain, or store a program for use by or in connection with an instruction execution system, apparatus, or device.

A computer readable signal medium may include a propagated data signal with computer readable program code embodied therein, for example, in baseband or as part of a carrier wave. Such a propagated signal may take any of a variety of forms, including, but not limited to, electromagnetic, optical, or any suitable combination thereof. A computer readable signal medium may be any computer readable medium that is not a computer readable storage medium and that can communicate, propagate, or transport a program for use by or in connection with an instruction execution system, apparatus, or device. Program code embodied on a computer readable signal medium may be transmitted using any appropriate medium, including but not limited to wireless, wireline, optical fiber cable, radio frequency ("RF"), etc., or any suitable combination of the foregoing.

Computer program code for carrying out operations for aspects of the present disclosure may be written in any combination of one or more programming languages, including an object oriented programming language such as Java, Scala, Smalltalk, Eiffel, JADE, Emerald, C++, C#, VB.NET, Python or the like, conventional procedural programming languages, such as the "C" programming language, Visual Basic, Fortran 2003, Perl, Common Business Oriented Language ("COBOL") 2002, PHP: Hypertext Processor ("PHP"), Advanced Business Application Programming ("ABAP"), dynamic programming languages such as Python, Ruby and Groovy, or other programming languages. The program code may execute entirely on the user's computer, partly on the user's computer, as a stand-alone software package, partly on the user's computer and partly on a remote computer or entirely on the remote computer or server. In the latter scenario, the remote computer may be connected to the user's computer through any type of network, including a local area network (LAN) or a wide area network (WAN), or the connection may be made to an external computer (for example, through the Internet using an Internet Service Provider) or in a cloud computing environment or offered as a service such as a Software as a Service (SaaS).

Various embodiments were described herein with reference to flowchart illustrations and/or block diagrams of methods, apparatus (systems), devices and computer program products according to various embodiments described herein. It will be understood that each block of the flowchart illustrations and/or block diagrams, and combinations of blocks in the flowchart illustrations and/or block diagrams, can be implemented by computer program instructions. These computer program instructions may be provided to a processing circuit of a general purpose computer, special purpose computer, or other programmable data processing apparatus to produce a machine, such that the instructions, which execute via the processing circuit of the computer or other programmable instruction execution apparatus, create a mechanism for implementing the functions/acts specified in the flowchart and/or block diagram block or blocks.

These computer program instructions may also be stored in a computer readable medium that when executed can direct a computer, other programmable data processing apparatus, or other devices to function in a particular manner, such that the instructions when stored in the computer readable medium produce an article of manufacture including instructions which when executed, cause a computer to implement the function/act specified in the flowchart and/or block diagram block or blocks. The computer program instructions may also be loaded onto a computer, other programmable instruction execution apparatus, or other devices to cause a series of operations to be performed on the computer, other programmable apparatuses or other devices to produce a computer implemented process such that the instructions which execute on the computer or other programmable apparatus provide processes for implementing the functions/acts specified in the flowchart and/or block diagram block or blocks.

The flowchart and block diagrams in the figures illustrate the architecture, functionality, and operation of possible implementations of systems, methods, and computer program products according to various aspects of the present disclosure. In this regard, each block in the flowchart or block diagrams may represent a module, segment, or portion of code, which includes one or more executable instructions for implementing the specified logical function(s). It should also be noted that, in some alternative implementations, the

functions noted in the block may occur out of the order noted in the figures. For example, two blocks shown in succession may, in fact, be executed substantially concurrently, or the blocks may sometimes be executed in the reverse order, depending upon the functionality involved. It will also be noted that each block of the block diagrams and/or flowchart illustration, and combinations of blocks in the block diagrams and/or flowchart illustration, can be implemented by special purpose hardware-based systems that perform the specified functions or acts, or combinations of special purpose hardware and computer instructions.

The terminology used herein is for the purpose of describing particular aspects only and is not intended to be limiting of the disclosure. As used herein, the singular forms "a", "an" and "the" are intended to include the plural forms as well, unless the context clearly indicates otherwise. It will be further understood that the terms "comprises" and/or "comprising," when used in this specification, specify the presence of stated features, steps, operations, elements, and/or components, but do not preclude the presence or addition of one or more other features, steps, operations, elements, components, and/or groups thereof. As used herein, the term "and/or" includes any and all combinations of one or more of the associated listed items and may be designated as "/". Like reference numbers signify like elements throughout the description of the figures.

Many different embodiments have been disclosed herein, in connection with the above description and the drawings. It will be understood that it would be unduly repetitious and obfuscating to literally describe and illustrate every combination and subcombination of these embodiments. Accordingly, all embodiments can be combined in any way and/or combination, and the present specification, including the drawings, shall be construed to constitute a complete written description of all combinations and subcombinations of the embodiments described herein, and of the manner and process of making and using them, and shall support claims to any such combination or subcombination.

What is claimed is:

1. A system comprising:
a processor circuit; and
a memory comprising machine-readable instructions that, when executed by the processor circuit, cause the processor circuit to:
provide a real-time environmental model of a shared virtual environment (SVE) comprising a plurality of virtual persons and a plurality of virtual gaming devices;
transmit display data corresponding to the SVE to a first player device worn by a first player, the display data comprising user display data that causes a display device in the first player device to render a portion of the SVE comprising a first wagering game at a first virtual gaming device of the plurality of virtual gaming devices based on a virtual orientation of the first player device and a virtual location of the first player in the SVE;
determine a player preference associated with the first player; and
based on the player preference, modify one of an appearance and a behavior of a first virtual person of the plurality of virtual persons in the SVE being displayed by the first player device, the modification further comprising display of a previously recorded behavior of a second player playing a second wager-

25

ing game at a second virtual gaming device of the plurality of virtual gaming devices as the first virtual person.

2. The system of claim 1, wherein a first subset of the plurality of virtual persons is associated with a plurality of respective players wearing a plurality of player devices, and wherein a second subset of the plurality of virtual persons comprise a plurality of system-controlled virtual persons. 5

3. The system of claim 2, wherein the first subset of the plurality of virtual persons comprises the first virtual person. 10

4. The system of claim 1, wherein the instructions further cause the processor circuit to modify virtual apparel being worn by the first virtual person.

5. The system of claim 1, wherein the instructions further cause the processor circuit to modify an apparent age of the first virtual person. 15

6. The system of claim 1, wherein the instructions further cause the processor circuit to modify a wagering style of the first virtual person.

7. The system of claim 6, wherein the instructions further cause the processor circuit to modify a game result reaction style of the first virtual person.

8. The system of claim 1, wherein the instructions further cause the processor circuit to:

transmit display data corresponding to the SVE to a second player device worn by a second player, the display data comprising user display data that causes a display device in the second player device to render a portion of the SVE based on a virtual orientation of the second player device and a virtual location of the second player in the SVE;

determine a player preference associated with the second player; and

based on the player preference of the second player, modify one of the appearance and the behavior of the first virtual person being displayed by the second player device to be different from the one of the appearance and the behavior being displayed by the first player device. 30

9. The system of claim 8, wherein the instructions further cause the processor circuit to:

transmit display data corresponding to the SVE to a third player device worn by a third player associated with the first player, the display data comprising user display data that causes a display device in the third player device to render a portion of the SVE based on a virtual orientation of the third player device and a virtual location of the third player in the SVE; 45

determine a player preference associated with the third player; and

based on the player preferences of the first player and the third player, modify one of the appearance and the behavior of the first virtual person being displayed by the first player device and the third player device. 50

10. The system of claim 1, wherein the instructions further cause the processor circuit to:

determine, based on the player preference of the first player and a location of the first player in the SVE, that the first virtual person is playing at a preferred virtual wagering game of the first player; and

in response to the determination, cause the first virtual person to leave the preferred virtual wagering game. 60

11. The system of claim 1, wherein the player preference comprises an occupancy preference comprising a preferred number of virtual persons in the SVE, and

wherein instructions further cause the processor circuit to; 65

26

determine that a virtual person associated with a second player has entered the SVE; and based on the occupancy preference of the first player, cause the first virtual person to leave the SVE to maintain the number of virtual persons in the SVE at the preferred number of virtual persons.

12. The system of claim 1, wherein the first virtual person corresponds to a system-controlled virtual customer service representative, and

wherein the instructions further cause the processor circuit to:

determine that the first player is interacting with the virtual customer service representative; and transfer control of the virtual customer service representative from the system to a customer service representative.

13. The system of claim 1, wherein the previously recorded behavior comprises the second player playing a wagering game.

14. A virtual-reality player device comprising: a head-wearable frame; a display device coupled to the frame to position the display device in a field of view of a player; a processor circuit; and

a memory comprising machine-readable instructions that, when executed by the processor circuit, cause the processor circuit to: receive display data corresponding to a shared virtual environment (SVE) comprising a plurality of virtual persons and a plurality of virtual gaming devices; render, by the display device, a portion of the SVE based on a virtual orientation of the gaming device and a virtual location of the player in the SVE; determine a player preference associated with the player;

based on the player preference, modify one of an appearance and a behavior of a first virtual person of the plurality of virtual persons in the SVE being displayed by the display device, the first virtual person corresponds to a system-controlled virtual customer service representative;

determine that the player is interacting with the virtual customer service representative; and transfer control of the virtual customer service representative from the system to a customer service representative.

15. A system comprising: a processor circuit; and

a memory comprising machine-readable instructions that, when executed by the processor circuit, cause the processor circuit to:

provide a real-time environmental model of a shared virtual environment (SVE) comprising a plurality of virtual persons and a plurality of virtual gaming devices;

transmit display data corresponding to the SVE to a first player device worn by a first player, the display data comprising user display data that causes a display device in the first player device to render a portion of the SVE based on a virtual orientation of the first player device and a virtual location of the first player in the SVE;

determine a player occupancy preference associated with the first player, the player occupancy preference comprising a preferred number of virtual persons in the SVE; and

determine that a virtual person associated with a second player has entered the SVE; and based on the player occupancy preference, cause another virtual person of the plurality of virtual persons to leave the SVE to maintain the number of virtual persons in the SVE at the preferred number of virtual persons.
